UNITED STATES PATENT OFFICE

HUGH M. STEPHENSON, OF FORT WAYNE, INDIANA, ASSIGNOR TO GENERAL ELECTRIC COMPANY, A CORPORATION OF NEW YORK

SEWING-MACHINE FEEDING MECHANISM

Application filed August 30, 1927. Serial No. 216,485.

My invention relates generally to sewing machines and more particularly to feeding mechanisms therefor.

Feeding mechanisms for sewing machines of the universal feeding type, as ordinarily constructed heretofore, have been of the over-feed type comprising rotatably adjustable mechanisms supported on the arm of the machine over the cloth plate and having a feed bar extending adjacent the cloth plate adapted to engage the material being sewn. These constructions are objectionable in that arranging the feeding mechanism on the arm of the machine necessarily results in a complicated structure which is difficult to enclose and which gives the machine a clumsy appearance.

In the usual form of unidirectional feeding mechanism having an oscillatory feed-dog, the material is fed under the presser-foot of the machine by teeth formed on the feed-dog adapted to engage and feed the material in one direction of its movement and adapted to freely slide under the material in the other direction of its movement. Universal under-feed mechanisms have been proposed in which a non-rotatably adjustable feed-dog has been oscillated in any direction by varying the adjustment of the mechanism so as to cause the mechanism to feed in the desired direction. Inasmuch as the feed-dog in these mechanisms has not been rotatably adjustable it has been necessary to form the teeth engaging the material so as to feed in any direction and also slide freely under the material in any direction. As a result these prior mechanisms have not positively fed the material during the sewing operation and frequently interrupt the feeding of material during the sewing operation by the feed-dog teeth engaging the material on its return stroke in which it should slide freely under the material.

An object of my invention is to provide a simple and effective universal feeding mechanism which will positively feed the material being sewn in any direction of adjustment and which can be readily adjusted to feed in any direction at will. I accomplish this by supporting a feed-dog beneath the presser-foot of the machine so it can be rotatably ad-

justed to feed in any direction and providing a mechanism for actuating the feed-dog in all directions of rotatable adjustment.

Another object of my invention is to provide a simple feed-dog actuating mechanism which is particularly adapted for use in my improved universal feeding mechanism, but which is also useful in any other form of feeding mechanism. I do this by supporting an oscillatory feed-dog on an axially movable member and providing means for oscillating said feed-dog in response to axial movement of said member.

A further object of my invention is to provide an improved stitch adjusting mechanism including a lever supported adjustably relative to tapering cams for actuating the same through ranges of movement dependent on the adjustment of the lever relative to the cams.

My invention will be more fully set forth in the following description referring to the accompanying drawing, and the features of novelty which characterize my invention will be pointed out with particularity in the claims annexed to and forming a part of this specification. In the drawing, Fig. 1 is a side elevation of a sewing machine embodying my invention partly broken away to more clearly show the construction; Fig. 2 is a bottom plan view of the machine shown in Fig. 1; Fig. 3 is a transverse sectional view of the machine shown in Figs. 1 and 2 showing the feed-dog at the beginning of its stroke; Fig. 4 is a view similar to Fig. 3 showing the feed-dog at the end of its stroke; Fig. 5 is a sectional view on the line 5—5 of Fig. 3; and Fig. 6 is a section on the line 6—6 of Fig. 4.

Referring to the drawing, I have shown my invention, for convenience in illustration, in connection with a rotary center bobbin type sewing machine comprising a bed-plate 10 having an overhanging arm 11 on which is supported the needle bar 12, take-up 13, and presser-foot 14. A loop-taker 15 is secured to a shaft 16 beneath the cloth plate of the machine and is operated in the necessary time relation to the needle bar 12 and take-up 13 by shafts and gearing extending through the arm 11 of the machine, includ-

ing a connection to the electric motor 17 for driving the machine.

The material M being sewn is fed under the presser-foot 14 during the operation of the machine by universal feeding mechanism which, in accordance with my invention, comprises an oscillatory feed-dog 18 supported on a rotatably adjustable and axially movable member 19 in such manner that the latter can be adjusted to change the path of oscillatory movement of the former to any desired direction under the presser-foot 14. This enables me to form the teeth 18^a on the feed-dog 18, which engage the material, so that they will positively feed the material in one direction and freely slide thereunder in the other direction. In order to facilitate the adjustment of the annular member 19, so as to vary the direction of feed of the mechanism, I arrange a lever 20 on the cloth plate 10 which is connected to the annular member by shafts and gearing including a pinion 21 engaging the toothed portion 19^a of the member 19, and secured to a shaft 22 provided with a flexible portion 22^a. The shaft 22 is supported at one end in a bearing 23 extending from the cloth plate 10 and at the other end in a slot 24 formed in a bracket 25 extending from the cloth plate. The pinion 21 is retained in engagement with the toothed portion 19^a of the member 19 by a spring 26 connected between the shaft 22 and the bracket 25. During the operation of the machine the annular member 19, which is slidably supported in the opening 10^b of the cloth plate, is raised and lowered which raises and lowers the pinion 21 against the action of the spring 26 so that in all positions of adjustment and vertical movement of the member 19 the connection is maintained with the adjusting handle 20.

Mechanism is provided for oscillating the feed-dog 18 in response to axial movement of the member 19 which is particularly adapted for use in my improved universal feeding mechanism, but which is also applicable to any feeding mechanism employing an oscillatory feed-dog. This mechanism comprises links 31 extending between the member 19 and the feed-dog, a plurality of supporting springs 27 arranged between the member 19 and the feed-dog 18 for supporting the feed-dog therein in a position of equilibrium at the beginning of its stroke adjacent the tip of the presser-foot 14 in the position of adjustment of the mechanism shown in the drawing, and headed stop pins 28 which prevent the feed-dog from rotating on the member 19 and limit its vertical movement relative thereto. The headed stop pins 28, which are secured to the feed-dog at 30, extend through slots 29 in the member 19, and the length of these pins 28 is such that the teeth 18^a of the feed-dog are lowered out of engagement with the material being sewn

when the member 19 is in its lowermost position and the springs 27 support the feed-dog 18 in its position of equilibrium at the beginning of its stroke. Vertical movement of the member 19, which is slidably supported in the opening 10^b of the cloth plate 10, moves the feed-dog toward the end of its stroke adjacent the heel of the presser-foot by the action of the links 31 as they are arranged between the member 19 and the feed-dog 18 in such position that they are slightly tilted from the vertical in the direction of movement of the feed-dog when it engages the material to feed it under the presser-foot. As the member 19 is raised from its lowermost position shown in Fig. 3 to its uppermost position, shown in Fig. 4, the links 31 move toward a horizontal position and move the feed-dog toward the heel of the presser-foot, compressing the springs 27 on the side of the feed-dog in the direction of feed, and elongating the springs 27 on the side of the feed-dog from which the material is fed. The tension of the presser-spring 14^a relative to the springs 27 supporting the feed-dog in the member 19 is adjusted by a screw 14^b so that when the member 19 moves downwardly in its cycle of operation from the position shown in Fig. 4 the feed-dog is lowered until the presser-foot clamps the material M against the throat-plate 10^a, and upon further downward movement of the member 19 the links 31 move toward an approximately vertical position, shown in Fig. 3, permitting the feed-dog to move to its position of equilibrium under the action of the springs 27 at the beginning of its stroke out of contact with the material M.

In order to raise and lower the member 19 for actuating the feed-dog, as above explained, and at the same time permit it to be rotatably adjusted to vary the direction of feed of the mechanism, I provide a forked lever 32, the prongs 33 of which slidably engage each side of the member 19, and the other end of which engages the bed-plate at 32^a. The lever 32 is adjustably supported from the cloth plate 10 by an adjusting pin 34 provided with a cam 35 and having a spring 36 thereon, arranged to yieldably support the lever in engagement with the cloth plate in such position that the cam 35 is aligned with the sides of the opening 32^b. The lever 32 is moved about its support so as to impart axial reciprocatory movement to the member 19 for actuating the feed-dog 18 by tapering cams 37 supported from the bracket 25 and provided with gears 38 which are driven by pinion 39 on the loop-taker shaft 16. The tapering cams 37 engage narrow bearing surfaces 32^c on the lever 32, as shown in Figs. 1 and 2, so that adjustment of the cam 35 by turning the pin 34 shifts the lever 32 relative to the cams 37 and changes the range of movement of the lever 130

32 about its support. Changing the range of movement of the lever 32 about its support correspondingly changes the range of vertical movement of the member 19 which lessens the range of oscillatory movement of the feed-dog 18 and shortens the stitch formed by the machine. It will be seen, by referring to Figs. 1 and 3, that the shifting of the lever 32 relative to the cams 37 slightly lowers the member 19, as this adjustment moves the bearing surfaces 32^a along the tapering cams 37 from the position in which it is illustrated. This lowers the position occupied by the feed-dog when it is in equilibrium under the action of the springs 27 at the beginning of its stroke and slightly increases the clearance between the teeth 18^a and the material M being sewn. Lowering the member 19 in this way does not change the relation of the links 31 to the feed-dog 18 and the member 19 because the stop pins 28 limit the vertical movement of the feed-dog 18 relative to the member 19. Inasmuch as the range of vertical movement of the member 19 is lessened by this adjustment it will now be apparent that the uppermost position of the member 19 will be somewhat lower than is shown in Fig. 4, so that the links 31 will not approach so nearly a horizontal position which will lessen the range of movement of the feed-dog toward the end of the stroke and shorten the stitch formed by the machine.

In operation of the sewing machine the needle, presser-foot and take-up cooperate with the loop-taker and my improved feeding mechanism to form stitches in the usual manner. The material M being sewn is fed under the presser-foot in the necessary time relation to the movement of the needle by the feed-dog 18. This time relation is obtained by the action of the cams 37 which are driven by the loop-taker shaft 16 and which raise and lower the lever 32 and the member 19 through a range of movement depending on the adjustment of the stitch controlling pin 34 which is determined by the position of the bearing surfaces 32^a relative to the tapering cams 37. The cycle of operation of the feed-dog in response to raising and lowering the member 19 under the action of the cams 37 is as follows: At the beginning of the stroke of the feed-dog the member 19 is in its lowermost position as shown in Figs. 1 and 3, so that the teeth 18^a of the feed-dog are slightly below the material M under the presser-foot and in equilibrium under the action of the springs 27. In this position the heads of the stop pins 28 abut against the member 19 limiting the separation of the feed-dog 18 and member 19 in which the links 31 are tilted slightly from the vertical in the direction of feed of the mechanism. When the feed-dog is in this position the cams 37 raise the member

19 by the lever 32 which brings the feed-dog into engagement with the material under the presser-foot and raises the presser-foot against the action of the presser-spring 14^a which releases the material M clamped between the presser-foot 14 and the throat-plate 10^a, and at the same time moves the feed-dog toward the heel of the presser-foot. At the end of the stroke the feed-dog 18 is in contact with the throat-plate 10^a and the links 31 are slightly tilted from a horizontal position as shown in Fig. 4. Further movement of the cams 37 lowers the feed-dog 18 and the member 19 without changing their relative position until the presser-foot 14^a so clamps the material M against the throat-plate 10^a. After the presser-foot clamps the material against the throat-plate the cams 37 continue to lower the member 19 which separates the member 19 from the feed-dog 18 and permits the links 31 to move to an approximately vertical position so that the feed-dog 18 slides under the material M to the beginning of its stroke. The stop pins 28 limit the downward movement of the member 19 relative to the feed-dog 18 and when the heads of the pins 28 come in contact with the member 19 the feed-dog is in a position of equilibrium under the action of the springs 27 and the links 31 are in an approximately vertical position. The cams 37 then slightly lower the member 19 and the feed-dog 18 as a unit until the teeth 18^a are slightly below the material M and the mechanism is in the position shown in Fig. 3 in which the feed-dog is at the beginning of its stroke. This cycle of operation of the feeding mechanism is continuously repeated during the operation of the machine. The operation of the feeding mechanism has been described in the position in which it feeds the material from the toe toward the heel of the presser-foot 14 but it is apparent that as the feed-dog 18 is mounted on the member 19 that it will be actuated in the same manner in all positions of rotatable adjustment of the member 19 and that the lever 32 will raise and lower the member 19 to actuate the feed-dog in any position of rotatable adjustment. The direction of feeding of the mechanism can be readily controlled by manipulation of the lever 20 which rotatably adjusts the position of the member 19 and the direction of the oscillatory movement of the feed-dog under the presser-foot.

Although I have described my universal feeding mechanism in connection with a rotary center bobbin sewing machine it is apparent that it is applicable as well to any other sewing machine. Moreover, it is apparent that modifications will occur to those skilled in the art of the embodiment of my invention herein disclosed. I desire it to be understood, therefore, that my invention is not limited to the particular arrangement

shown and described, and I intend in the appended claims to cover all modifications which do not depart from the spirit and scope of my invention.

What I claim as new and desire to secure by Letters Patent of the United States is:

1. In a sewing machine having a cloth-plate, a universal feeding mechanism comprising a feed-dog arranged below the top of said cloth-plate, a vertically movable member, means for supporting said member so as to provide for rotatable adjustment of the same, means for supporting said feed-dog on said member and for actuating the same to feed material in response to vertical movement of said member in any position of rotatable adjustment so that the feeding mechanism can be adjusted to feed in all directions.
2. In a sewing machine having a cloth-plate, a universal feeding mechanism comprising a feed-dog arranged below the top of said cloth-plate, a vertically movable member, means for supporting said member so as to provide for rotatable adjustment of the same, means including a spring between said feed-dog and said member tending to maintain the former in one position relative to the latter, and means for actuating said feed-dog to feed material in response to vertical movement of said member in any position so that the feeding mechanism can be adjusted to feed in all directions.
3. In a sewing machine having a cloth-plate, a universal feeding mechanism comprising a feed-dog arranged below the top of said cloth-plate, a vertically movable member, means for supporting said member so as to provide for rotatable adjustment of the same, means including a spring between said feed-dog and said member tending to maintain the former in one position relative to the latter, and means including links between said member and said feed-dog for actuating the latter in response to vertical movement of said member in any position so that the feeding mechanism can be adjusted to feed in all directions.
4. In a sewing machine having a bed-plate, a universal feeding mechanism comprising a feed-dog arranged below the top of said bed-plate, a vertically movable annular member, means for supporting said member to provide for rotatable adjustment of the same, means including a plurality of substantially radially arranged springs between said feed-dog and said member tending to maintain said feed-dog in the center of said member, and means including links between said member and said feed-dog for actuating the latter in response to vertical movement of said member in any position of rotatable adjustment so that the feeding mechanism can be adjusted to feed in all directions.

5. In a sewing machine having a presser foot and a bed-plate, said bed-plate having a cylindrical bore below said presser foot, a universal feeding mechanism including a feed-dog co-operating with said presser foot arranged in said bore and arranged below the top of said bed-plate, a vertically movable annular member arranged in said bore, means for supporting said member to provide for rotatable adjustment and axial movement thereof, means including a plurality of springs between said feed-dog and said member tending to maintain the feed-dog substantially in the center of said member, and means including a plurality of links between said member and said feed-dog for actuating the latter in response to vertical movement of said member in any position so that the feeding mechanism can be adjusted to feed in all directions.

6. In a sewing machine having a cloth-plate, a feeding mechanism comprising an oscillatory feed-dog arranged below the top of said cloth-plate, an axially movable annular member, springs between said annular member and said feed-dog, and means co-operating with said springs for actuating said feed-dog to feed material in response to axial movement of said annular member.

7. In a sewing machine having a cloth-plate, a feeding mechanism comprising an oscillatory feed-dog arranged below the top of said cloth-plate and a presser-foot having a spring urging said presser-foot against said feed-dog, an axially movable annular member, springs between said annular member and said feed-dog, and means cooperating with said springs and said presser-foot for actuating said feed-dog to feed material in response to axial movement of said annular member.

8. In a sewing machine, a cloth-plate having an opening therein, a universal feeding mechanism comprising a rotatably adjustable and axially movable member extending into the opening in said cloth plate, a feed-dog mounted on said rotatable member, and means for actuating said feed-dog to feed material in response to axial movement of said member in all positions of rotatable adjustment so that the mechanism can be adjusted to feed in all directions.

9. In a sewing machine having a cloth-plate, a universal feeding mechanism comprising a rotatably adjustable and axially movable member, an oscillatory feed-dog mounted on said member, means for actuating said feed-dog to feed material in response to axial movement of said member, means for rotatably adjusting said member throughout the range of its axial movement and for yieldably retaining the same at one end of its range of movement, and means for axially moving said member in all positions of rotatable adjustment so that the mecha-

nism can be adjusted to feed in all directions.

10. In a sewing machine having a cloth plate, a universal feeding mechanism comprising a horizontally disposed annular member, said member being rotatably adjustable and axially movable, an oscillatory feed-dog supported on said member, means for axially moving said member including a forked lever supported at one end from said cloth plate, the prongs of said lever slidably engaging each side of said member so that the mechanism can be adjusted to feed in all directions, and means responsive to axial movement of said member for actuating said feed-dog to feed material.

15. In a sewing machine having a cloth plate, a universal feeding mechanism comprising a rotatably adjustable and axially movable member, an oscillatory feed-dog supported on said member, a rotatable cam, a forked lever supported at one end from said cloth plate, the prongs of said lever engaging said member, said cam being arranged to engage said lever intermediate the ends thereof for moving the same about its support so as to axially move said member, and means responsive to axial movement of said member for actuating said feed-dog to feed material.

20. In a sewing machine having a cloth plate, a universal feeding mechanism comprising a rotatably adjustable feed-dog, and means for oscillating said feed-dog in all positions of rotatable adjustment including a lever supported at one end from said cloth plate and a cam engaging said lever for moving the same about its support, said lever and cam being relatively adjustable to vary the range of oscillatory movement of said feed-dog.

25. 13. In a rotary sewing machine having a cloth plate and a loop-taker shaft, a universal feeding mechanism comprising an oscillatory feed-dog, a rotatably adjustable and axially movable member for supporting said feed-dog, a lever having one end supported from said cloth plate and the other end engaging said member, a rotatable cam driven by said loop-taker shaft and arranged to engage said lever for moving the same about its support, means for adjusting said lever relative to said cam for varying the range of oscillatory movement of said feed-dog, and means for yieldably retaining said member against said lever and for rotatably adjusting said feed-dog to feed in all directions.

30. 14. In a sewing machine having a cloth plate and a loop-taker shaft, a universal feeding mechanism comprising an oscillatory feed-dog, a rotatably adjustable and axially movable member for supporting said feed-dog, a lever having one end supported from said cloth-plate and the other end forked to engage said member on opposite sides thereof, and a plurality of rotatable cams driven by said loop-taker shaft, each

of said cams being arranged to engage a branch of said forked lever for moving the same about its support.

35. 15. In a sewing machine having a cloth-plate and a loop-taker shaft, a universal feeding mechanism comprising an oscillatory feed-dog, a rotatably adjustable and axially movable member for supporting said feed-dog, a lever having one end supported from said cloth-plate and the other end forked to engage said member on opposite sides thereof, a plurality of rotatable cams driven by said loop-taker shaft and each being arranged to engage a branch of said forked lever, for moving the same about its support, and means for adjusting said lever relative to said cam for varying the range of oscillatory movement of said feed-dog.

40. 16. In a sewing machine having a cloth-plate and a loop-taker shaft, a universal feeding mechanism comprising an oscillatory feed-dog, a rotatably adjustable and axially movable member for supporting said feed-dog, a lever having one end supported from said cloth-plate and the other end forked to engage said member on opposite sides thereof, a plurality of rotatable cams driven by said loop-taker shaft, each being arranged to engage a branch of said forked lever for moving the same about its support, and means for yieldably retaining said member against the forks of said lever and for rotatably adjusting said feed-dog to feed in all directions.

45. In witness whereof, I have hereunto set my hand this 26th day of August, 1927.

HUGH M. STEPHENSON.
